United States Patent Office

Des. 189,818
Patented Feb. 28, 1961

189,818

CHAIR FOR BARBER OR BEAUTY SHOP

Fred J. Piotraschke, 8032 Carondelet Ave., Clayton, Mo.

Filed May 16, 1960, Ser. No. 60,614

Term of patent 14 years

(Cl. D15—3)

Fig. 3

Fig. 4

Figure 1 is a front perspective view of my new chair.
Figure 2 is a top plan view of the chair.

Figure 3 is a side elevational view of the chair.

Figure 4 is a rear elevational view of the chair.

I claim:

The ornamental design of a chair for barber and beauty shop, as shown.

References Cited in the file of this patent

UNITED STATES PATENTS

D. 144,068	Piotraschke	-----	Mar. 5, 1946
D. 177,557	Dlouhy	-----	May 1, 1956
D. 180,404	Osaka	-----	June 4, 1957

OTHER REFERENCES

Koch Cat. No. 77, dated October 30, 1958, page 4.
item K6650, barber chair.